(57) **CLAIM**

The ornamental design for a motion sensor safe light, as shown and described.

DESCRIPTION

FIG. 1 is a perspective view of a motion sensor safe light as viewed from the top and front.

FIG. 2 is a top plan view thereof.

FIG. 3 is a bottom plan view thereof.

FIG. 4 is a front side profile view thereof.

FIG. 5 is a back side profile view thereof.

FIG. 6 is a side profile view thereof; and,

FIG. 7 is a second side profile view thereof.

The details shown in broken lines illustrate features that form no part of the claimed designs.
